Primary Examiner — Mitchell Siegel(74) *Attorney, Agent, or Firm* — Banner & Witcoff, Ltd.**CLAIM**

The ornamental design for a golf club head, as shown and described.

DESCRIPTION

FIG. 1 is a perspective view of a golf club head showing our new design;

FIG. 2 is a rear view thereof;

FIG. 3 is a heel end view thereof;

FIG. 4 is a toe end view thereof;

FIG. 5 is a bottom view thereof; and,

FIG. 6 is a top view thereof.

The broken lines immediately adjacent to the shaded area represent unclaimed boundaries of the design. The broken lines showing the remainder of the golf club head are for environmental purposes only and form no part of the claimed design.
